CONTROL SYRINGE

Fred Naftolin, 2746½ S. Sepulveda Blvd., and Duane E. Townsend, 3271 S. Sepulveda Blvd., both of Los Angeles, Calif.

Filed Aug. 26, 1964, Ser. No. 81,441

Term of patent 14 years

(Cl. D83—12)

FIGURE 1 is a perspective view of the control syringe of our invention;

FIGURE 2 is a top plan view thereof;

FIGURE 3 is a front elevational view thereof; and
FIGURE 4 is an end elevational view thereof.

The undisclosed rear portion of the syringe is substantially the same as the front portion illustrated in FIG. 3 except for the omission of the graduated scale. The dominant features of our design reside in the portions shown in full lines.

We claim:

The ornamental design for a control syringe, substantially as shown and described.
